ROD MILL FEEDING MEANS

Henry L. Genier, Silver Bay, Minn., assignor to Reserve Mining Company, Silver Bay, Minn., a corporation of Minnesota

Filed Nov. 23, 1960, Ser. No. 71,219
3 Claims. (Cl. 241—171)

The present application is a continuation-in-part of our co-pending application, Serial Number 735,029, filed May 13, 1958, now abandoned.

This invention relates to novel and improved feed chute means for discharging fragmented material into a grinding mill wherein it can be further ground and refined.

By way of example, and not of limitation the invention will be illustrated in an adaptation wherein ore fragments are discharged from an endless conveyor, and then fed into a rod mill by the feed chute means to be hereinafter described.

The rod mill is rotating continuously on a substantially horizontal axis, and must have end heads to retain the rods and the material to be ground. Obviously the said material is most efficiently charged through an axial opening in an end head and the feed chute must closely approach or preferably extend into said opening, or into a neck or similar extension of the end head. Since the entering material is usually a fragmented ore and water mixture, hereinafter for convenience termed a sludge, the operation is normally attended by a certain amount of leakage at the zone of entry. Likewise, certain comminuted ores, such as taconite, are hard and highly abrasive, and feed chutes of this type wear away rapidly and heretofore have needed frequent replacement.

Feed chutes have been previously developed containing sealing means completely surrounding the discharge end of a discharge chute. Such sealing means have temporarily proven effective, but in the presence of certain highly abrasive materials such as fragmented or comminuted taconite, some of the fragmented material becomes lodged between the complementary stationary and rotating elements of the sealed joint and this material progresses around with the rotating element. As a result there is excessive wear on a resilient sealing gasket.

An object of the present invention, therefore, is to provide a feed chute having sealing means at the zone of juncture of the rod mill end head and the chute discharge end.

A further object of the invention is to provide means for materially reducing wear of the sealing means mentioned in the immediately preceding paragraph.

A further object of the invention is to provide a feed chute having easily replaceable wear proof liner portions to reduce shut-down time for repairs.

A further object of the invention is to provide an automatically self-cleaning sealing means at the discharge end of the chute.

Other objects and advantages will be apparent from a study of the following description of one embodiment of the invention, in conjunction with the accompanying drawings, in which:

FIG. 1 is a vertical sectional view, taken approximately axially through the feeding end of a rod mill, and showing my novel feed chute in working position.

FIG. 2 is a top plan view of the feed chute as seen from the position of the line 2—2 of FIG. 1, and somewhat enlarged.

FIG. 3 is a side elevational view of the feed chute, with a part broken away and in section to reveal part of the internal structure.

FIG. 4 is an end view of the feed chute, as seen from the right end of FIG. 3.

2

FIG. 5 is a vertical sectional view taken on the line 5—5 of FIG. 3.

FIG. 6 is a sectional view taken on the lines 6—6 of FIG. 4, showing details of a fragmentary portion of the stationary feed chute; adjacent portion 32, 51, of the rotating drum structure are added to illustrate their juxtaposed relationship.

FIG. 6A is a sectional view taken on the line 6A—6A of FIG. 4, and, as in FIG. 6, adjacent portions 32, 51, of the rotating drum structure are shown to illustrate the relationship of the fixed and movable members.

FIG. 7 is an end elevational view as seen from the position of the line 7—7 on FIG. 3.

Referring first to FIG. 1 there is shown the charging 15 end of a cylindrical rod mill 19 which may be about ten feet in diameter and sixteen feet long, these dimensions being merely exemplary of the magnitude of the apparatus. A ring gear 20 is fixed to a flange at the end of the rod mill and has peripheral teeth 20a which mesh with 20 a drive pinion here shown in outline at 21. This pinion and a motor with direct driving means (not shown) may be mounted on a fixed platform at any convenient height, being shown at the bottom in FIG. 1 merely for a graphic illustration of the operating mechanism. Obviously rotation of the pinion and gear produces rotation 25 of the drum around its horizontal axis "A."

The drum is journaled for rotation in end bearings, one being shown in FIG. 1, and being the usual semicircular sleeve bearings 22 carried on a pillar 23. The drum has 30 an end head 24 attached to a bonnet 25 by bolts 26. The bonnet is provided with a hollow hub 25a, the outer periphery of which is machined to rotate in the aforesaid bearings 22. Attached to the outer end of the hub is a retaining ring 27. A frusto-conical neck 32 is secured 35 by retaining ring 27 against bonnet 25. The neck 32 serves as a flared inlet passage to receive the fragmented material from the feed chute and permit it to discharge into the drum 19.

Still referring to FIG. 1, the fragmented ore may be 40 delivered in a number of ways, for instance on an endless conveyor 35 which passes over an end roll 36 and discharges downwardly through a partially enclosed housing 37 supported on structural uprights 38, only one being shown. The feed chute now to be described has an upper 45 flanged surface 34 readily attachable to or detachable from the lower edge of housing 37.

The feed spout assembly is shown in FIGS. 2 to 7. It includes a short length 39 of steel pipe, cut away at 50 several places to accommodate additional structure. At its upper or inlet end I have provided a hopper made from steel sheets, having two end walls 40 and 41 and two side walls 42 and 43. Wall 41 is arched to fit over the top of pipe 39 and is welded to the pipe as best seen in FIG. 4. Wall 40 is contoured to be attached by bolts 55 to a shaped frame 44 welded to the end of the pipe. The inner faces of walls 41, 42 and 43 carry wear plates 41a, 42a and 43a which are tailored to fit the exposed wall surfaces, and are made of hard, wear-resistant alloy, the plates being attached to their respective walls by readily 60 detachable means, such as bolts or the like, shown at 47 in FIGS. 3 and 5.

The lower inner wall of pipe 39 carries wear resistant 65 lining means of semi-cylindrical shape, consisting in the present case of three parts identified by reference characters 48, 49 and 50 (FIGS. 3, 4 and 5). These liners also are attached by bolts as shown for example in FIG. 5. These, and the wall liners previously described, are readily removable and replaceable, so that the same supporting shell can be used indefinitely.

At the lower or discharge end of the chute, pipe 39 70 is cut away, just as within the hopper, but for a different

purpose. Since the chute is used in an inclined position, and preferably extends within the cupped inlet port 30, the pipe must be cut away in the particular embodiment shown, so as to conform to one or more transverse flanges within the cup.

The delivery or discharge end of the pipe carries a ring or collar which is insertible into a port in the rotatable end head of the drum. As indicated in FIGS. 1, 3, 4, 6 and 6A an external sealing member or gasket 53 is carried on the outer peripheral surface of the collar. The collar consists of a ring 54 having an inturned circumferential flange 55 to which the sealing member is attached in any convenient way, for example by machine screws 56. This assembly comprising the gasket 53, the ring 54, and the flange 55, is arcuately cut away to provide a gap approximately sixty degrees in width at the top as best shown in FIG. 4, the gap extending between terminal faces 54a on the collar and gasket. The gasket is formed from rubber or rubber-like material and the collar 54, 55 and its gasket are telescopically inserted into the aperture in rotatable wearing ring 51 which is carried by the spoked segment 52 of neck 32.

The arcuate ring 54 in turn is supported on another ring 57 which has a central aperture fitting snugly around the discharge end of pipe 39. The feed chute is provided with a pair of lugs 58 (FIG. 4) which are located at the vertical plane of the center of gravity so that the chute can be lifted by a portable crane hoist sling with a pair of terminal hooks. This is convenient when locating the chute with respect to the conveyor and the rotating drum.

The upper end wall 40 of the chute hopper is perforated to receive a water inlet nozzle 62 which can be connected by a pipe 63 with a source of water under pressure. Water admitted at this point will wash the ore fragments or other material downwardly into the grinding mill, the delivery end of the nozzle being shaped to inject the water angularly against the chute bottom so that the water not only facilitates delivery of the material but also increases its mobility during grinding. The line S in FIG. 1 indicates the normal operating sludge level within 40

The cooperation between the stationary feed pipe assembly, carrying the sealing ring 53, and the rotating mill trunnion assembly, carrying seal wearing ring 51, is most important since the relative sliding contact between the seal 53 and the ring 51 must be accurate enough so that the ring 51 "bites" slightly into the resilient material of the ring so as to prevent outward leakage at their arcuate zone of contact.

With the construction as shown in the drawings, wherein an arcuate portion of the upper periphery of the seal and its supporting ring is cut away, any entrapped fragmented material is now carried circumferentially around by the rotation of the mill and ring 51 until said fragmented material reaches the cut-away segment of stationary sealing member 53. At this point said fragmented material is no longer entrapped, and drops freely downwardly into feed pipe 39. This provides an automatically self-cleaning seal which materially increases the life of the sliding seal elements 51 and 53.

What is claimed is:

1. In a material-grinding apparatus of the character described wherein a cylindrical grinding drum is being rotated on a horizontal axis, and wherein said drum has a substantially vertically disposed end wall provided with an axially located inlet port therein, means for charging fragmented material sludge into said inlet port comprising a feed chute having a delivery end including a collar surrounding and carried by said delivery end, and fitted to be insertible into said port, and a sealing gasket of resilient material surrounding and attached to said collar and operatively contacting the internal periphery of said port whereby to prevent outward leakage of sludge, said gasket and said collar having aligned segmental portions cut from an upper portion thereof to provide an aperture whereby material entrapped between the outer surface of said gasket and the inner peripheral edge of said port is permitted to drop inwardly through said aperture and into the delivery end of said chute during rotation of said drum.

2. In a material-grinding apparatus of the character described, a grinding drum rotatable on a horizontal axis and having an end wall disposed transversely to said axis, said end wall having a circular inlet port axially located therein, a feed chute having a circular material-delivering end insertible in said port, a resilient sealing gasket surrounding and fixed on said material-delivering end and providing a sealing contact between the wall of said chute end and the rotatable inner peripheral edge surface of said port, an upper portion of said gasket and a registered upper portion of said material delivering end being cut away to provide an aperture whereby material entrapped between the outer surface of said gasket and the inner peripheral edge of said port is permitted to drop inwardly through said aperture and into said material-delivery end of said chute during rotation of said drum.

3. In a material-grinding apparatus of the character described wherein a cylindrical grinding drum is being rotated on a horizontal axis, and wherein said drum has a substantially vertically disposed end wall provided with an axially located inlet port therein, means for charging fragmented material sludge into said inlet port comprising a feed chute having a delivery end including a collar surrounding and carried by said delivery end, and fitted to be insertible into said port, said collar having a segmental upper portion cut therefrom to provide an aperture whereby material entrapped between the outer surface of said collar and the inner peripheral edge of said port is permitted to drop inwardly through said aperture and into the delivery end of said chute during rotation of said drum.
